His ATTORNEY.

UNITED STATES PATENT OFFICE.

JOHN T. ROWLEY, OF PITTSBURGH, PENNSYLVANIA.

MOLD.

1,112,937.

Specification of Letters Patent.

Patented Oct. 6, 1914.

Application filed January 28, 1913. Serial No. 744,637.

To all whom it may concern:

Be it known that I, JOHN T. ROWLEY, a citizen of the United States, residing at Pittsburgh, in the county of Allegheny and State of Pennsylvania, have invented a new and useful Improvement in Molds, of which improvement the following is a specification.

My invention relates to improvements in molds for the production of billets, bars, rods, or other metallic forms which are to be subsequently reduced by rolling, hammering or otherwise.

The object of my invention is to produce a mold by the use of which billets, bars, etc., may be continuously produced, that is, poured and cooled sufficiently to be discharged therefrom in comparatively solid condition, or the said mold may be used successively to produce a number of billets.

Having this object in view my invention consists in the novel construction and arrangement of parts hereinafter more specifically described, reference being had to the accompanying drawings, in which—

Figure 1 is a longitudinal sectional view of the mold. Figs. 2, 3 and 4 are details of the lower portion of the same showing the separable gate.

Referring to said drawings, 1 is a casting, floor, platform or support, having a recess 2 in which a funnel shaped opening 3 is formed, the brick or block in which said opening is formed being made of any suitable refractory material and communicating directly with the central orifice 4 through the support 1, which coincides in the cross sectional area with the interior cavity 5 of the mold. The said mold comprises an interior compartment 5 surrounded by walls 6. The upper end of said mold is screw threaded in order to be secured to the support 1, or it may be secured to said support in any other suitable manner. The said walls are surrounded by a water jacket 7, which is likewise screw threaded and secured to said support. The said water jacket is provided with an inlet 8 and a discharge 9 for the purpose of admitting

and discharging constantly water for the purpose of lowering the temperature of the mold. It is noted also that the water jacket is made in two sections and that where said sections abut or come close together an expansible joint 10 is provided for the purpose of taking care of the expansion and contraction that may take place in the walls of the water jacket. It is also noted that the lower end of the mold terminates in a separable portion 11, which is capable of being separated for the purpose of permitting the discharge of the cooled or cooling ingot, etc., the said lower part being formed in two sections, each of which is provided with a boss, 13, 13, under which the free end of the counterbalanced lever 14 engages to keep said lower end in position until the metal is sufficiently cooled. The metal when cooled contracts sufficiently to enable the same to be discharged readily upon opening the lower end of the mold. The lever is merely shown in conventional manner. It is noted also that the interior bore of the mold tapers from the top to the bottom so as to permit the ready discharge of the cooled contents, and that said mold is also provided with an overflow discharge 12.

The advantages of my mold will be apparent to those skilled in the art to which it appertains.

Having described my invention, what I claim and desire to secure by Letters Patent is:

A mold the lower end of which is closed by a gate adapted to be opened to discharge the contents of the mold, a water jacket formed in two sections surrounding said mold, and an expansible joint connecting said sections, substantially as described.

In testimony whereof, I have hereunto signed my name in the presence of two subscribing witnesses.

JOHN T. ROWLEY.

In the presence of—
CLARENCE A. WILLIAMS,
JOHN H. RONEY.
